Primary Examiner — Thomas Johannes

Assistant Examiner — Shawn T Gingrich

(74) Attorney, Agent, or Firm — Polsinelli PC

CLAIM

The ornamental design for cabinet for electrical switchboards, as shown and described.

DESCRIPTION

FIG. 1 is a isometric view of an embodiment of the new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.
